CLAIM

The ornamental design for a rotating fidget device, as shown and described.

DESCRIPTION

FIG. 1 is a perspective view of the rotating fidget device embodying my new design

FIG. 2. is a front view thereof;

FIG. 3. is a rear view thereof;

FIG. 4 is a right view thereof;

FIG. 5 is a left view thereof; and,

FIG. 6 is a top view thereof.

My rotating fidget device is characterized by triangular prism body with a rotatable triangular prism attachment.
